UNITED STATES PATENT OFFICE.

CHRISTIAN F. RUMOLD, OF BEEA, KENTUCKY.

RAILWAY SIGNAL APPARATUS.

1,141,147.

Specification of Letters Patent. Patented June 1, 1915.

Application filed August 12, 1913. Serial No. 784,392.

To all whom it may concern:

Be it known that I, CHRISTIAN F. RUMOLD, a citizen of the United States, residing at Berea, in the county of Madison and State of Kentucky, have invented certain new and useful Improvements in Railway Signal Apparatus, of which the following is a specification.

My invention relates to automatic block signals and its object is to use electric current for this purpose in such a way as will admit of more powerful batteries or other source of current being used with less waste of current during periods of clear track, or other conditions of safety, and with a correspondingly greater certainty of a prompt signal under conditions of danger.

A further object is to insure that the failure of any battery or other part of the mechanism will make itself known immediately and automatically.

My invention consists in the parts and in the details of construction and arrangement of parts as will hereinafter be more fully described and claimed.

In the drawing: Figure 1 is a diagram of the arrangement of block signals for a single track, according to my invention. Fig. 2 is a similar diagram of the arrangement of the signals in connection with a turn-out and its switch. Fig. 3 is a similar diagram of the arrangement of the signals in connection with double track and a crossover and its switches. Fig. 4 is a similar diagram of the arrangement of the signals in connection with intersecting tracks. Fig. 5 is a diagram similar to Fig. 1, but showing how additional signaling apparatus is provided to guard against accidents at some particularly dangerous place along the track such as the sharp curve represented; this diagram also shows how the various apparatus may be connected in multiple and the current supplied by a dynamo electric machine.

Referring to Fig. 1, the single track, comprising the rails 1 and 2, is divided into blocks A, B, C, D, E, F and G, which may be of any convenient length, from several hundred feet to several miles. The rails 1 and 2 are insulated from each other except such conduction as is incident to wooden ties, and the blocks above designated are defined by suitable insulations 3 and 4, which divide the rails 1 and 2, re-

spectively, into series of continuous conductors running the length of the respective blocks, but insulated from each other, as well as from the respective rails of the other blocks. The rails at each side of the track in each block may be made electrically continuous by any suitable bonding means.

Near the end of each block, on one side of the track, is the signal apparatus 5 and near the end of each block on the left hand side of the track is the apparatus 6. My system involves the use of some form of electro-magnetic motive apparatus to actuate the signal, and the motor 5 or 6 represents said apparatus, whether it be a motor designed for continuous rotation or some other form of electro-magnetically actuated motive apparatus. Likewise, each motor 5 and 6 is provided with a battery 7 and 8, respectively, which represents some form of electric current source, and may be a local battery of any suitable form, or may be some form of dynamo-electric machine, either local or at a central station or substation. The localization of the batteries 7 and 8 with respective ones of the motors 5 and 6 simplifies the diagram, but it will be understood that it is necessary only that individual current supply be provided for each motor, and this may be effected by means of individual circuits leading from a central source of supply to the various motors along the line. In some cases the provision of individual batteries for the motors may be preferable. In any event, the supply of current from the sources 7 and 8 to the respective motors 5 and 6 is under the control of the relays 9 and 10 provided for the motors individually. As herein illustrated, each relay 9 has two coils 11 and 12 and each relay 10 has two coils 13 and 14 preferably wound in the same direction. The relay is so adjusted that when either of its coils is deenergized the motor circuit is open, and the torque manifested on the motor shaft or other operative part of the motive apparatus ceases. The armature or other resistance of the motive apparatus, and the voltage of the battery 7 or 8, may be relatively high, to avoid overheating while exerting the torque against the stationary resistance.

As I have illustrated my invention, and as I prefer to install it, a condition in any certain block will be signaled at the farther

105

110

ends of the next adjacent two blocks in both directions along the track. Thus a condition in block D of Fig. 1 will be signaled by the apparatus located, respectively, at the 5 farther end of the block C and at the farther end of the block B, and this apparatus will be designated BC⁵ and AB⁵, respectively, for convenience of reference. Also this condition in block D will be signaled at the farther ends of the blocks E and F, by the apparatus 10 6 thereat, respectively, and which apparatus for convenience of reference will be designated EF⁶ and FG⁶, respectively. To accomplish this, an arrangement of relays is provided for each block, and controlling circuits that include coils of the 15 relays 9 and 10, respectively, of the apparatus 5 and 6, lying in the respective directions along the track. For sake of clearness, and 20 on account of lack of space, only the relay arrangement for block B is shown in Fig. 1, but conductors leading from the signal apparatus of other blocks to other relay arrangements are indicated, as will be later described. Thus, two relays 15 and 16, of relatively 25 high resistance, and a third relay 17, of relatively low resistance, are provided for each block. The relay 15 has one end of its coil connected by a conductor 18 to the rail 1 at the end of the block D adjacent to the block C, and the other end of the coil of this relay 15 is connected through a conductor 19, battery 20 and conductor 21 to the rail 1 at the other end of the block 30 35 D adjacent to the block E. Thus a circuit is made including the entire length of the rail 1 within the block D along with the coil of the relay 15 and with the battery 20, and as long as the rail 1 forms a continuous conductor along with the other conductors 18, 19 and 21 the relay 15 will be energized.

The relay 16 has one end of its coil connected by a conductor 22 to the rail 2 at the 40 end of block D adjacent to the block C, and the other end of the coil of this relay 16 is connected by a conductor 23 through a battery 24 and a conductor 25 to the rail 2 at the other end of the block D adjacent to the block E. Thus the entire length of the rail 50 55 2 within the block D forms a circuit along with the coil of the relay 16 and the battery 24, and as long as this rail 2 forms a continuous conductor along with the other conductors 22, 23 and 25 the relay 16 will be energized.

The third relay 17 has one end of its coil connected by a conductor 26 to the conductor 19 of the relay 15 and battery 20, and has the other end of its coil connected by a conductor 27 to the conductor 23 of the relay 16 and battery 24. The batteries 20 and 24 are so arranged in their respective circuits that when a circuit is completed through both of them by way of the coil of the relay 60 65 17, positive and negative poles of the respec-

tive batteries will be connected, and the aggregate out-put of the two batteries will thus be obtained in this circuit.

By the above arrangement, if the two rails 1 and 2 in the block D become electrically 70 connected, the aggregate current of the two batteries 20 and 24 will flow through the circuit of lesser resistance around the coils of the relay 17, so that the currents of the respective batteries 20 and 24 through the 75 coils of the relays 15 and 16, theretofore flowing, will be reduced almost to *nil*, and the relays 15 and 16 will be practically de-energized, while the relay 17 will be strongly energized by the aggregate current of the 80 batteries 20 and 24.

The levers of these three relays 15, 17 and 16 are in series, in the order mentioned, in a circuit that includes coils of the relays 9 of the apparatus BC⁵ and AB⁵, and of the 85 relays 10 of the apparatus EF⁶ and FG⁶. The connections in this circuit are so made that the levers of the relays 15 and 16 keep the circuit closed as long as these relays 15 and 16 are energized, but so that the lever 90 of the relay 17 keeps the circuit closed only when this relay 17 is de-energized. Being in series, the breaking of contact by any one of these levers opens circuit and de-energizes the respective relays 9 and 10, which in turn 95 allow the circuits of the apparatus BC⁵ and AB⁵ and EF⁶ and FG⁶ to open, eliminating the torque on the motive parts of the apparatus. The circuit, controlled by the relays 15, 17 and 16, includes the battery or other 100 current source 28, which energizes the relays 9 and 10 when the circuit is closed by all of the relays 15, 17 and 16 having their levers making contact. Under these conditions, thus provided by my invention, a 105 break in either rail 1 or 2 of the block D will de-energize either the relay 15 or the relay 16, respectively. The circuit controlled by these relays and supplied by the 110 battery 28 will open, and the torque on the signal apparatus at the farther ends of the adjacent two blocks will be removed and the signal device will be allowed to assume a position indicating danger. Also, if a vehicle or any other obstruction within block 115 D forms electrical connection between the two rails 1 and 2, a strong current will be caused to flow through the coils of the relay 17, energizing it and opening the circuit at this point, with the same result, *i. e.*, relieving the torque on the signal apparatus and bringing about the display of the danger signal. Even though the relays 15 and 16 be not de-energized by diverting the current 120 from them to the relay 17, the circuit will be 125 opened by the relay 17, nevertheless. Thus, de-energization of either relay 15 or 16, or energization of the relay 17, either singly, or any two, or all such actions simultaneously, will open the circuit of the battery 28. 130

Not only will the actual breakage of the rail or the actual presence of obstruction in block D cause the display of the danger signal at the ends of the other blocks, but any breakage in the conductors connected to the relays 15 and 16 will cause a warning to be given by the signal apparatus. Thus, the contingency of there being an obstruction in block D, accompanied with failure of one of the conductors leading to a single rail, thus failing to signal the danger, is avoided. It will be seen that the breakage of one of the conductors forming the circuit through the relay 17, such as the conductors 21 and 25, would result in a failure of the relay 17 to operate and signal the presence of the obstruction; but this breakage of either of these conductors would deenergize either the relay 15 or 16, and the danger signals would be displayed, nevertheless.

From the above description it will be seen that when the vehicle is proceeding along the block A and there is a condition of danger in the block D, the vehicle will receive a signal by the apparatus AB⁵ but should it have reached the block B before the condition of danger exists in block D, the vehicle will still receive a signal from the apparatus BC⁵ while it is still the entire length of the block C from block D. In the first instance it would have had the entire length of block B and C for stoppage after the signal was received.

35 A vehicle traveling away from block D in block E will receive a signal of any condition of danger in block D through apparatus EF⁶, and if it has reached block F, before the danger exists in block D, it will still receive a signal from the apparatus FG⁶. This signaling of danger at the rear of the vehicle is important when another vehicle is following, preventing rear-end collision. The vehicle following will of course receive the signals showing the presence of the vehicle running ahead.

By means of the double coils 11 and 12 of the relays 9, and 13 and 14 of the relays 10, each two adjacent relays along the line, on the same side, are included in a circuit with another two relays adjacent along the line on the other side of the track, with two relays, adjacent to each other along the track, intervening on each side of the track, these intervening ones being connected in two other circuits, respectively, on the two sides of the track. Thus each relay is in circuit with the relays adjacent to it in both directions along the track, but by means of distinct coils, maintaining the circuits distinct, so that the circuits are controlled by different blocks. Thus the relay 9 of apparatus BC⁵ is in circuit with the relay 9 of apparatus AB⁵ and controlled by the relays 15, 17 and 16 of block D as fully illustrated;

but it is also in circuit with the relay 9 of apparatus CD⁶ and this circuit would be controlled through the circuit 29 by relays similar to those of block D, but connected to the rails of block E through conductors 70 30. Similarly, the relays 10 of apparatus EF and FG are in circuit and controlled by the relays 15, 17 and 16 along with the relays 9 of the apparatus AB and BC; but relay 10 of apparatus EF is also in circuit 75 with the relay 10 of apparatus DE and would be controlled through a circuit 31 by relays similar to the relays 15, 17 and 16, but connected with the rails of block C by the conductors 32. This arrangement is 80 continuous along the two sides of the track in opposite directions on respective sides, so that each block along the track is connected to the signal devices at the respective 85 farther entrances of the two blocks adjacent in either direction along the track, with the apparatus on the right indicating the condition in this block to a vehicle approaching in either direction and the apparatus on the left indicating the condition in this block to a vehicle running away from the block in either direction.

In Fig. 2 is illustrated how an ordinary turn-out from the main line is included as a separate block of the main line, so that if the 95 switch is open, or a vehicle is left on the turn-out or siding, or not "in the clear", danger signals will be given at the farther ends of the adjacent two blocks in both directions. As here shown, the turn-out 33 is 100 toward the side of the track having the rail 1, and the turn-out rail 34 is continuous with the rail 1 of the main line and a point rail 35 is brought up thereto, at the same time drawing the other point rail 36 away from the rail 2 of the main line, thus allowing the vehicle to pass along the main line. This point rail 36 is continuous with the other rail 37 of the turn-out or siding, which rail 37 105 crosses the rail 1 of the main line by means 110 of a frog 38, and is insulated at both sides of the frog 38 by suitable insulating means 39, while a conductor 40 makes it electrically continuous around the frog 38. These rails 34 and 37 of the siding are provided with 115 insulators 41 and 42 placed at such a point that if a vehicle is so close to the main line that it will not be "in the clear" on this siding it will extend over these two insulators 41 and 42 and electrically connect the rails 34 and 37 within this block thus defined by these insulators. A lever 43 is made to move with the point rails 35 and 36, and is included as a part of the conductor 21 that 120 connects from the rail 1 at one end of the block through the battery 20 and conductor 19 to one end of the coil of the relay 15. This lever 43 is so arranged that as long as the switch is thrown to allow the vehicle to 125 proceed along the main line the circuit will 130 135

be closed. The rail 34, being continuous with the rail 1, will also form part of this circuit for purposes of connecting with the other rail 37 of the siding to signal an obstruction on the siding, as before mentioned. The other conductor 18, for the relay 15, leads from the rail 1 at the extreme other end of the block as before described in connection with Fig. 1, and the conductor 22 10 leads from the rail 2 at that end of the block to the relay 16, while the other conductor, connecting through the battery 24 and conductor 23 to the relay 16, leads to the rail 2 at the other end of the block as in Fig. 1. 15 The rail 37 of the siding has electrical connection 44 with the rail 2 of the main line and its point rail 36 is insulated from the lever 43 by the mounting 45 of the lever. It will be seen that the relay 17 will be operated by the connection of rails 1 and 2 or by connection of rails 34 and 37 of the siding. The signal apparatus 5 and 6 for the respective blocks are the same as described in connection with Fig. 1 and the adjacent 25 blocks are designated A, B and C and E, F and G, as in Fig. 1 while the block set apart for the switch or turn-out is designated DS. Signals of the condition of the switch and turn-out will thus be given to approaching vehicles by apparatus AB⁵ and BC⁶ in one direction and by apparatus EF⁶ and FG⁶ in the other direction.

Fig. 3 illustrates the arrangement of my apparatus with double track and a cross-over from one track to the other. It will be assumed that the vehicles run from top to bottom of the figure on the first track represented at the left, and this track is divided into blocks A, B, C, DD, E, F, and G, the section DD being set apart for the cross-over. On the other track, on which the vehicles run in the opposite direction, the blocks are, reading from bottom to top of the figure, H, J, K, LL, M, N, and O, the block LL being the one that includes the cross-over where it leads from this track. On account of lack of space, the tracks in the regions of the blocks DD and LL are shown close together, but in the regions of the other blocks are shown far enough apart to admit the parts of the diagram illustrating the signal apparatus along the inner sides of the two tracks.

All of the blocks, including the cross-over blocks DD and LL, are similar to those of Figs. 1 and 2, each with rails 1 and 2 separated by insulators 3 and 4, respectively, and provided with the signal apparatus 5 and 6 adjacent to the rails of each track, respectively. Each track has its independent series of signal apparatus arranged along in the blocks as has been described in connection with Fig. 1, and this apparatus, shown in Fig. 3 for the two blocks next adjacent to the cross-over block in each direc-

tion and on each track, as at AB, BC, GF and FG, for the first track and at HJ, JK, ON and MN, for the other track, are all connected through one of the coils of the relay 9 or 10 of each signal apparatus with apparatus of other blocks, not shown, in the manner that has been described in connection with Fig. 1. Thus, each block DD and LL have these connections, making the signal system for each of the two tracks independent, but these connections are not shown here, it being merely the purpose to show how the cross-over, as distinguished from the main track in the cross-over blocks, is provided with signal apparatus. This cross-over comprises the two rails 46 and 47, the rail 46 being mechanically continuous with the rail 1 of the block LL and the rail 47 being mechanically continuous with the rail 2 of the block DD. The rail 47 has the insulator 48 interposed close to its junction with said rail 1, and the rail 47 has the insulator 49 interposed close to its junction with the rail 2 of the other track. Where said cross-over rails 46 and 47 cross the rails 2 and 1 of the two tracks, they have frogs 50 and 51, respectively. The frog 50 is flanked by insulators 52 and 52 and the frog 51 by insulators 54 and 55, so that the rails 46 and 47 are insulated from the rails 2 and 1 which they cross. The rail 46 is made electrically continuous around the frog 50 by a conductor 56 and the rail 47 is made similarly continuous around the frog 51 by a conductor 57. The rail 46 terminates in the block DD with a point rail 58, which may be brought up against the rail 1 and is insulated from, but mechanically connects by a bar 59 with the point rail 60, so as to draw said point rail 60 away from the continuous rails 2 and 47, to allow a vehicle to pass over toward the other track. Connected to the bar 59 is a lever 61, on an insulating mounting 62 so as to be properly insulated from the point rail 60, but connected to the point rail 58 by a conductor 63. At the other end of the cross-over, in the block LL, the rail 47 terminates in a point rail 64, which may be brought up against the rail 2 of the block LL and is insulated from but connected by a bar 65 with the other point rail 66, to draw the point rail 66 away from the continuous rails 1 and 46 at the other side of the track, so that a vehicle may pass over toward the other track. A lever 67 is shifted with these point rails, having an insulating mounting 68 so that it is properly insulated from the point rail 64, and so arranged that when the point rails 64 and 66 are shifted to allow the vehicle to pass along the block LL, this lever 67 will make electrical contact with a conductor 69, which is connected to the rail 46, beyond the insulator 48 from this switch. One end of the coil of the relay 15 is con-

nected by the conductor 19, through the battery 20 and the conductor 21, to the lever 67 in the block LL. The other end of the coil of the relay 15 has the conductor 18 leading 5 up to the other end of the block DD to the lever 61, which lever is so arranged that when the point rails 58 and 60 are shifted to allow the vehicle to pass straight along the block DD, this lever 61 will make elec- 10 trical contact with this conductor 18. One end of the coil of the relay 16 is connected by the conductor 22 with the cross-over rail 47, beyond the insulator 49 from the switch in the block DD. The other end of the coil 15 of the relay 16 is connected by the conductor 23, through the battery 24 and the conductor 25, to the point rail 64 of the switch in the block LL. Thus, the normal circuit 20 in which the coil of the relay 15 is included is by the way of the conductor 18 to the lever 61, through the conductor 63 to the cross-over rail 46, therealong to the conductor 69, through the lever 67, and from there through the conductor 21, battery 20, and 25 conductor 19, back to the relay 15. Similarly, the normal circuit of the relay 16 is by the way of the conductor 22 to the rail 47 beyond the insulator 49 from the switch in the block DD, along said rail 47 to its 30 point rail 64 in the other block LL, and from there through the conductor 25, battery 24, and conductor 23, back to the relay 16. If a vehicle or other obstruction occupy 35 the cross-over electrically connecting the two rails 46 and 47, the aggregate current of the batteries 20 and 24 will flow through the relay 17 by the way of the conductors 26 and 27, as previously described in connection with Figs. 1 and 2. If either of the 40 rails 46 and 57 be broken, or if any of the conductors connecting them to their respective relays 15 and 16 be broken, the respective relay will be deenergized. Accordingly, a breakage of either circuit by breaking 45 contact on throwing either switch and shifting of the lever 61 or lever 67, will cause the respective relay 15 or 16 to be deenergized. In any case, either by energizing the relay 17 at the expense of the relays 50 15 and 16, or by the deenergization of either relay 15 or 16, signals will be given by the signal apparatus AB⁵ and BC⁵ and GF⁶ and FE⁶ on the one track, and by the apparatus HJ⁶ and JK⁶ and ON⁵ and MN⁵ of the other 55 track. It will thus be seen that if either switch of the cross-over be thrown to permit a vehicle to pass over to the other track from that on which it is traveling, the signals will be given in the other blocks, as has 60 been described. It will be noted that, even though, for instance, merely the switch in the block LL be left open, the danger signal will be given to vehicles approaching 65 from either direction toward the block DD on the other track, where the switch is in proper position and will not itself result in disaster to the vehicle running in block DD. This precaution is as it should be, since a vehicle running in block LL and being diverted over to the other track will be 70 a menace to any vehicle running on the other track in the block DD, owing to liability of collision of the two vehicles at the cross-over.

In Fig. 4 the intersection frog X is insulated by means of the insulators 70 from all the rest of the two intersecting tracks. The rails 1 and 2 of the track represented as running from top to bottom of the figure are made continuous around the insulated 75 frog X by conductors 71 and 72, respectively, while the rails 1 and 2 of the other track are insulated around the frog by conductors 73 and 74, respectively. Insulators 80 3 and 4 divide the two tracks into blocks, 85 those blocks of the track running from top to bottom being designated A, B, C, at one side of the intersection and D, F, and G at the other side. Those of the other side are designated P, Q and R at one side of the 90 intersection and S, T and U at the other side, the first described track has the block DX set apart between the blocks C and E to include the intersection and the other track has the block VX similarly set apart 95 between the blocks R and S. The blocks DX and VX have their rails 1 and 2 and 2 and 1 connected in series through conductors 75 and 75^a, respectively, and are provided with a set of relays 15, 16 and 17, with the corresponding connections and batteries as described in connection with Fig. 1, and these relays control the signal apparatus of both tracks. It will thus be seen that a vehicle occupying either the intersection block DX 100 or the intersection block VX will cause a signal to a vehicle approaching on either track at the beginning of the block Q and of the block R in one direction, and at the beginning of the block T and of the block 105 S in the other direction, on one track, or at the beginning of the block B and of the block C in one direction and at the beginning of the block F and the block E in the other direction on the other track, as the 110 case may be. The other coils of the relays 9 and 10 of the respective signal apparatus are connected to the apparatus by continuing blocks along the respective intersecting 115 lines in the manner described in connection 120 with Fig. 1.

The arrangement shown in Fig. 5 represents the various blocks A, B, C, D, E, F and G, provided with signaling apparatus with motors 5 and 6 at their junctions as 125 in Fig. 1. Instead of the batteries 7, 8, 20, 24 and 28, however, leads 76 and 77, from a dynamo electric machine 78, have the various apparatus connected to them in multiple, as will be described later.

Additional signal apparatus with motors 79 and 80 are provided at the approaches to the sharp curve in the block D, in either direction on opposite sides of the track. These 5 motors 79 and 80 are controlled by relays 81 and 82, respectively, and the current through the coils of the relays is under the control of the relays 15, 16 and 17 of this block D, in which this extra signal apparatus 10 is located. Therefore, when a vehicle 83 enters block D, electrically connecting the rails 1 and 2 thereof, a circuit will be closed through the coil of the relay 17 and the motors 79 and 80 will be deprived of their 15 current and will display danger signals to the vehicle as it approaches the sharp curve in either direction.

A provision may be made for any dangerous part of the track where it is desired that 20 the vehicle should slow down in passing the place or come to a full stop before passing the place. Such places may be grade crossings, track intersections, unsafe bridges, or other unsafe parts of the track where it 25 may be desired to compel precaution in running over such parts of the track.

The motors 5 and 6, opposite to each other at each block intersection, have a conductor 30 84, in common, from the lead 76, connected to corresponding brushes of the two motors, while the other brush of each motor is connected to the contact point of the relay 9 or 10, respectively. The contact bars of the relays 9 and 10 are connected to the other lead 35 77 by conductors 85 and 86 respectively. Thus through these conductors 84, 85 and 86, connected to the leads, the dynamo 78 supplants the batteries 7 and 8 of Fig. 1.

40 Each circuit in which coils of relays 9 and 10 are included receives current from the leads 76 and 77, through conductors 87 and 88, 89 and 90. Thus, by means of the conductors 87, 88, 89 and 90, the dynamo 78 supplants the battery 28 of Fig. 1. The 45 circuits including the coils of the relays 15, 16 and 17, and also including the rails 1 and 2 of the track as hereinbefore described, here receive their current from the leads 76 and 50 77 through conductors 91 and 92, whereby the dynamo 78 supplants the batteries 20 and 24 of Fig. 1.

It will be understood that such an arrangement is applicable with the other cases 55 such as exemplified in Figs. 2, 3 and 4. This arrangement will be found especially convenient where current is supplied along the line from a central or sub-station as in electric railroad work.

60 The motors 79 and 80, of the extra signaling apparatus shown, have a conductor 93, in common, connected to the lead 76; the conductors 94 and 95 lead from the motors 79 and 80 to their respective relays 81 and 65 82 for the contact bars of the relays to make

or break connection with; and conductors 96 and 97 connect the contact bars of the relays 81 and 82 with the leads 76 and 77, respectively. Since these extra apparatus are peculiar to the particular region of the track where they are provided, they are 70 merely placed in series with each other and with relays 9 of apparatus AB⁵ and BC⁶ and the relays 10 of the apparatus GF⁶ and FE⁶, so that these relays 81 and 82 need have 75 but one coil each, as indicated. Thus, one end of the coil of relay 81 is connected to an end of the coil of the relay 82 by the conductor 98, and the other ends of the coils are connected to conductors 99 and 100, respectively which cut into the circuit of the 80 relays 9 and 10 of the other apparatus, which circuit also includes the contact bars of the relays 15, 16 and 17, with the result that this extra apparatus is operated in unison with the regular apparatus as above described.

The above examples illustrate how my invention is applied to the various track arrangements, and it will be understood that the details of the apparatus may vary considerably to adapt the system to particular 90 conditions. Wherever batteries are referred to, it will be understood that current derived from any other generating source, such as a 95 dynamo, may be used; and also that the relays referred to may be of any desired construction, or may be represented by any suitable electrically operated switches or cut-outs, according to the strength of current 100 and other conditions to be met with in any particular installations.

In view of the foregoing I do not wish to be understood as being limited to the precise illustrations and description herein 105 given as examples of the application of my invention, but

What I claim as new and desire to secure by Letters Patent is:

1. In railway signal apparatus, the combination with rails of a track substantially 110 electrically insulated from each other, and respectively divided into sections longitudinally of the rails, said sections being insulated from each other, thereby forming 115 blocks, of motor apparatus for each block, electro-magnetic means for controlling the motor apparatus by energization and de-energization of the means, three separate 120 electro-magnetic means controlling current supply to the aforesaid means, one of these three means being in a circuit including one rail of one of the blocks substantially from one end of the block to the other, and another of these means being likewise in a 125 circuit with the other rail of said block, and the third one of these means being in a circuit depending for completion upon electrical connection of the one rail to the other rail of said block, the first and second ones 130

of these means being normally energized but the third one of these means being normally deenergized, and becoming energized on the connection of said two rails together, any 5 one of these three means being alone capable of affecting the motor-apparatus-controlling means, and a source of current for the respective electro-magnetic means.

2. In railway signal apparatus, the combination with rails of a track substantially 10 electrically insulated from each other, and respectively divided into sections longitudinally of the rails, said sections being insulated from each other, thereby forming 15 blocks, of motor apparatus for each block, electro-magnetic means for controlling the motor apparatus by energization and deenergization of the means, three separate electro-magnetic means controlling current supply 20 to the aforesaid means, one of these three means being in a circuit including one rail of one of the blocks substantially from one end of the block to the other, and another of these means being likewise in a circuit 25 with the other rail of said block, and the third one of these means being in circuit depending for completion upon electrical connection of the one rail to the other rail of said block, this last means being of 30 lower resistance than the first and second ones of these means and being normally deenergized while the first and second of these means are normally energized, and, upon connection of said two rails together, current 35 being shunted from said first and second means to this last means of lower resistance and thereby energizing it, any one of these three means being capable of affecting the motor-apparatus-controlling means, and a source 40 of current for the respective electro-magnetic means.

3. In railway signal apparatus the combination with rails of a track substantially 45 electrically insulated from each other, and respectively divided into sections longitudinally of the rails, said sections being insulated from each other, thereby forming blocks, of motor apparatus for each block, electro-magnetic means for controlling the 50 motor apparatus by energization and deenergization of the means, a set of three separate electro-magnetic means to each block controlling current supply to the aforesaid means of some other block, one of these three 55 means being in a circuit including one rail of one of the blocks substantially from one end of the block to the other, and another of these means being likewise in a circuit with the other rail of said block, and the 60 third one of these means being in a circuit depending for completion upon electrical connection of the one rail to the other rail of said block, the first and second ones of these means being normally energized but the 65 third one of these means being normally deenergized and becoming energized on the connection of said two rails together, any one of these three means being alone capable of affecting the respective motor-apparatus- 130

deenergized and becoming energized on the connection of said two rails together, any one of these three means being alone capable of affecting the respective motor-apparatus-controlling means, and a source of current 70 for the respective electro-magnetic means.

4. In railway signal apparatus, the combination with rails of a track substantially 75 electrically insulated from each other, and respectively divided into sections longitudinally of the rails, said sections being insulated from each other, thereby forming blocks, of motor apparatus for each block, electro-magnetic means for controlling the motor apparatus by energization or deenergization of the means, a set of three separate electro-magnetic means to each block, controlling current supply to the aforesaid means of an adjacent block, one of these three means being in a circuit including one 80 rail of one of the blocks substantially from one end of the block to the other, and another of these means being likewise in a circuit with the other rail of said block, and the third one of these means being in a circuit 85 depending for completion upon electrical connection of the one rail to the other rail of said block, the first and second ones of these means being normally energized, but the third one of these means being normally deenergized and becoming energized on the connection of said two rails together, any one of these three means being alone 90 capable of affecting the respective motor-apparatus-controlling means, and a source 95 of current for the respective electro-magnetic means.

5. In railway signal apparatus, the combination with rails of a track substantially 100 electrically insulated from each other, and respectively divided into sections longitudinally of the rails, said sections being insulated from each other, thereby forming blocks, of motor apparatus for each block, electro-magnetic means for controlling the 105 motor apparatus by energization and deenergization of the means, three separate electro-magnetic means to each block controlling current supply to the aforesaid means of two next adjacent blocks, one of these 110 three means being in circuit including one rail of the block substantially from one end of the block to the other, and another of these means being likewise in a circuit with the other rail of said block, and the third 115 one of these means being in a circuit depending for completion upon electrical connection of the one rail to the other rail of said block, the first and second ones of these means being normally energized but the third one of these means being normally deenergized and becoming energized on the connection of said two rails together, any one of these three means being alone capable 120 of affecting the respective motor-apparatus- 125

130

controlling means, and a source of current for the respective electro-magnetic means.

6. In railway signal apparatus, the combination with rails of a track substantially electrically insulated from each other, and respectively divided into sections longitudinally of the rails, said sections being insulated from each other, thereby forming blocks, of motor apparatus for each block, 10 electro-magnetic means to each block for controlling the motor apparatus by energization and deenergization of the means, three separate electro-magnetic means to each block, controlling current supply to the 15 aforesaid means of an adjacent block in each direction along the track, one of these three means being in a circuit including one rail of the block substantially from one end of the block to the other, and another of these 20 means being likewise in a circuit with the other rail of said block, and the third one of these means being in a circuit depending for completion upon electrical connection of the one rail to the other rail of said block, the first and second ones of these means being normally energized but the third one of these means being normally deenergized and becoming energized on the connection of 25 said two rails together, any one of these three means being alone capable of affecting the respective motor-apparatus-controlling means, and a source of current for the respective electro-magnetic means.
7. In railway signal apparatus, the combination with rails of a track substantially electrically insulated from each other, and respectively divided into sections longitudinally of the rails, said sections being insulated from each other, thereby forming blocks, of motor apparatus for each block, 30 electro-magnetic means for controlling the motor apparatus by energization and deenergization of the means, three separate electro-magnetic means to each block, controlling current supply to the aforesaid means of the next two adjacent of said blocks in each direction along the track, one of these three means being in a circuit including one rail of the block substantially from one end of the block to the other, and another of these 35 means being likewise in a circuit with the other rail of said block, and the third one of these means being in a circuit depending for completion upon electrical connection of the one rail to the other rail of said block, the first and second ones of these means being normally energized but the third one of these means being normally deenergized and becoming energized on the connection of 40 said two rails together, any one of these three means being alone capable of affecting the respective motor-apparatus-controlling means, and a source of current for the respective electro-magnetic means.
8. In railway signal apparatus, the combination with rails of a track substantially electrically insulated from each other, and respectively divided into sections longitudinally of the rails, said sections being insulated from each other, thereby forming blocks, of motor apparatus for each block, 45 electro-magnetic means for controlling the motor apparatus by energization and deenergization of the means, three separate electro-magnetic means to each block, controlling current supply to the aforesaid means of the next two adjacent of said blocks in each direction along the track, one of these three means being in a circuit including one rail of the block substantially from one end of the block to the other, and another of these 50 means being likewise in a circuit with the other rail of said block, and the third one of these means being in a circuit depending for completion upon electrical connection of the one rail to the other rail of said block, the first and second ones of these means being normally energized but the third one of these means being normally deenergized and becoming energized on the connection of 55 said two rails together, any one of these three means being alone capable of affecting the respective motor-apparatus-controlling means, and a source of current for the respective electro-magnetic means.
9. In railway signal apparatus, the combination with rails of a track substantially electrically insulated from each other, and respectively divided into sections longitudinally of the rails, said sections being insulated from each other, thereby forming blocks, of motor apparatus for each block, 60 electro-magnetic means for controlling the motor apparatus by energization and deenergization of the means, three separate electro-magnetic means to each block, controlling current supply to the aforesaid means of adjacent blocks in each direction along the track on opposite sides of the track in the respective directions, one of these three means being in a circuit including one rail of the block substantially from one end of the block to the other, and another of these means being likewise in a circuit with the other rail of said block, and the third one of these means being in a circuit depending for 65 completion upon electrical connection of the one rail of said block to the other rail of said block, the first and second ones of these means being normally energized, but the third one of the means being normally de-

nated with rails of a track substantially electrically insulated from each other, and respectively divided into sections longitudinally of the rails, said sections being insulated from each other, thereby forming blocks, of motor apparatus for each block, electro-magnetic means for controlling the motor apparatus by energization and deenergization of the means, three separate electro-magnetic means to each block, controlling current supply to a respective one of the aforesaid means, one of these three means being in a circuit including one rail of the block substantially from one end of the block to the other, and another of these means being likewise in a circuit with the other rail of said block, and the third one of these means being in a circuit depending for completion upon electrical connection of the one rail to the other rail of said block, the first and second ones of these means being normally energized but the third one of these means being normally deenergized and becoming energized on the connection of said two rails together, any one of these three means being alone capable of affecting the respective motor-apparatus-controlling means, a source of current for the respective electro-magnetic means, each motor-apparatus-controlling means having two coils, one coil being in series with one of the coils of the corresponding means adjacent along the track in one direction and the other coil being in series with one of the coils of the corresponding means adjacent along the track in the other direction, each two coils thus in series being in a circuit affected by the set of another block than the one to which said motor-apparatus-controlling means belongs.

9. In railway signal apparatus, the combination with rails of a track substantially electrically insulated from each other, and respectively divided into sections longitudinally of the rails, said sections being insulated from each other, thereby forming blocks, of motor apparatus for each block, electro-magnetic means for controlling the motor apparatus by energization and deenergization of the means, three separate electro-magnetic means to each block, controlling current supply to the aforesaid means of adjacent blocks in each direction along the track on opposite sides of the track in the respective directions, one of these three means being in a circuit including one rail of the block substantially from one end of the block to the other, and another of these means being likewise in a circuit with the other rail of said block, and the third one of these means being in a circuit depending for completion upon electrical connection of the one rail of said block to the other rail of said block, the first and second ones of these means being normally energized, but the third one of the means being normally de-

energized and becoming energized on the connection of said two rails together, any one of these three means being capable of affecting the respective motor-apparatus-controlling means, and a source of current for the respective electro-magnetic means.

10. In railway signal apparatus, the combination with rails of a track substantially electrically insulated from each other, and respectively divided into sections longitudinally of the rails, said sections being insulated from each other, thereby forming blocks, of motor apparatus for each block, electro-magnetic means for controlling the motor apparatus by energization and de-energization of the means, three separate electro-magnetic means to each block, controlling current supply to the aforesaid motor-apparatus-controlling means of two next adjacent blocks in each direction along the track and on opposite sides of the track in the respective directions, one of these three means being in a circuit including one rail of the block substantially from one end of the block to the other, and another of these means being likewise in a circuit with the other rail of said block, and the third one of these means being in a circuit depending for completion upon electrical connection of the one rail of said block to the other rail of said block, the first and second ones of these means being normally energized, but the third one of these means being normally deenergized and becoming energized on the connection of said two rails together, any one of these three means being capable of affecting the respective motor-apparatus-controlling means, the aforesaid set of means of each block affecting the motor controlling apparatus of the next two adjacent blocks along the track in either direction and on opposite sides of the track in the respective directions, each of said motor apparatus controlling means having two coils, one of said coils being in series with one of the coils of the corresponding means next adjacent in one direction along the track and the other coil being in series with one of the coils of the corresponding means next adjacent in the other direction, each two coils thus in series being in circuit for control by the set of the block as aforesaid, and in circuit with the two coils of said motor-apparatus-controlling means in the other direction from said block on the other side of the track.
11. In railway signal apparatus, the combination with rails of a track substantially electrically insulated from each other, and respectively divided into sections longitudinally of the rails, said sections being insulated from each other, thereby forming

blocks, of motor apparatus for each block, electro-magnetic means for controlling the motor apparatus by energization and de-energization of the means, a set of three separate electro-magnetic means to each block, controlling current supply to a respective one of the aforesaid means, one of these means being in a circuit including one rail of the block substantially from one end of the block to the other, and another of these means being likewise in a circuit with the other rail of said block, and the third one of these means being in a circuit depending for completion upon electrical connection of the one rail of said block to the other rail of said block, the first and second ones of these means being normally energized, but the third one of these means being normally deenergized and becoming energized on the connection of said two rails together, any one of these three means being capable of affecting the respective motor-apparatus-controlling means, the aforesaid set of means of each block affecting the motor controlling apparatus of the next two adjacent blocks along the track in either direction and on opposite sides of the track in the respective directions, each of said motor apparatus controlling means having two coils, one of said coils being in series with one of the coils of the corresponding means next adjacent in one direction along the track and the other coil being in series with one of the coils of the corresponding means next adjacent in the other direction, each two coils thus in series being in circuit for control by the set of the block as aforesaid, and in circuit with the two coils of said motor-apparatus-controlling means in the other direction from said block on the other side of the track.

CHRISTIAN F. RUMOLD.
